Primary Examiner — Karen S Acker*(74) Attorney, Agent, or Firm* — Shumaker, Loop &
Kendrick, LLP(57) **CLAIM**The ornamental design for a fastening device for rain
screens, as shown and described.

DESCRIPTION

1. Fastening device for rain screens

1.1 : Isometric

1.2 : Isometric

1.3 : Top

1.4 : Left

1.5 : Bottom

1.6 : Right

1.7 : Front

1.8 : Back
